CLAIM

The ornamental design for a sensor platform, as shown and described.

DESCRIPTION

FIG. 1 is a front, top, and left side perspective view of the sensor platform showing the new design according to a first embodiment.

FIG. 2 is a rear, bottom, and right side perspective view of the sensor platform showing the new design according to a first embodiment.

FIG. 3 is a top view of the sensor platform showing the new design according to a first embodiment.

FIG. 4 is a bottom view of the sensor platform showing the new design according to a first embodiment.

FIG. 5 is a side view of the sensor platform showing the new design according to a first embodiment.

FIG. 6 is a front view of the sensor platform showing the new design according to a first embodiment.

FIG. 7 is a rear view of the sensor platform showing the new design according to a first embodiment.

FIG. 8 is a front, top, and left side perspective view of the sensor platform showing the new design according to a second embodiment.

FIG. 9 is a rear, bottom, and right side perspective view of the sensor platform showing the new design according to a second embodiment.

FIG. 10 is a top view of the sensor platform showing the new design according to a second embodiment.

FIG. 11 is a bottom view of the sensor platform showing the new design according to a second embodiment.

FIG. 12 is a side view of the sensor platform showing the new design according to a second embodiment.

FIG. 13 is a front view of the sensor platform showing the new design according to a second embodiment; and, FIG. 14 is a rear view of the sensor platform showing the new design according to a second embodiment.

(Continued)

Within the drawings, the straight-line surface shading show the character and contour of the surfaces in the claimed design of the sensor platform. The broken lines show unclaimed portions of the sensor platform, and thus form no part of the claimed design.
